US0D1110939S

(12) **United States Design Patent** (10) Patent No.: **US D1,110,939 S**
(45) Date of Patent: ** Feb. 3, 2026

(54) **SOLAR CONTROLLER HOUSING**

(71) Applicant: **Junxuan Chen**, Shenzhen (CN)

(72) Inventor: **Junxuan Chen**, Shenzhen (CN)

(**) Term: **15 Years**

(21) Appl. No.: **29/934,011**

(22) Filed: **Mar. 22, 2024**

(51) LOC (15) Cl. **13-02**

(52) U.S. Cl.

USPC **D13/102**; D13/162

CLAIM

The ornamental design for a solar controller housing, as shown and described.

DESCRIPTION

FIG. 1 is a front, top perspective view of a solar controller housing, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the solar controller housing that form no part of the claimed design.

1 Claim, 8 Drawing Sheets
